CENTER DRAWER HOUSING FOR PEDESTAL
TYPE DESKSHerbert W. Deutemeier, Cincinnati, Ohio, assignor
or to The Globe-Wernicke Co., Norwood, Ohio,
a corporation of Ohio

Application February 18, 1947, Serial No. 729,362

8 Claims. (Cl. 45—93)

1

This invention relates to a center drawer housing for pedestal type desk and has to do with certain features of construction whereby the housing is removable.

The modern metal pedestal type desk is made up generally of two pedestals, one of these being a right and one a left pedestal and these pedestals are provided on the side which will be in the knee hole space with a center drawer housing or runner. Such desks may or may not have a skirt across the knee hole space on the side opposite the user, and a separate top is laid on the pedestals and fastened thereto.

Because of the fact that the center drawer housings have heretofore been permanently secured to the pedestal walls the pedestals themselves have always been unsymmetrical and it has always been necessary to provide rights and lefts.

From the standpoint of production it is desirable that all pedestals be the same, so that any two pedestals can be used together in a desk without regard to whether they are rights or lefts.

It is therefore an object of my invention to provide a construction by which all desk pedestals may be uniform, so that any pedestal may either be a right or a left pedestal depending upon which side of the pedestal the housing for the center drawer is mounted.

It is another object of my invention to provide a housing as a separate unit which may easily and quickly be attached to the pedestal.

It is a further object of my invention to make the housings in rights and lefts but to provide the pedestals with means whereby either a left housing can be used on one side thereof, or a right housing on the other side so that given a pair of housings (right and left) and a pair of pedestals (identical) either of the pedestals may be made the right pedestal or left pedestal.

It is a still further object of my invention to provide a construction whereby the housing is caused to hug the pedestal wall tightly so that it will be free of rattles.

These and other objects of my invention which will be pointed out in more detail hereinafter or which will be apparent to one skilled in the art upon reading these specifications, I accomplish by that certain construction and arrangement of parts of which I shall now describe an exemplary embodiment.

Reference is made to the drawings forming a part hereof and in which:

Fig. 1 is a front elevation of a desk to which my invention may be applied.

2

Fig. 2 is a plan view of the same with part of the top broken away to show the construction.

Fig. 3 is a fragmentary view with parts in cross section on the line 3—3 of Fig. 1 and with the center drawer removed, on an enlarged scale.

Fig. 4 is a fragmentary cross sectional view taken on the line 4—4 of Fig. 3 on a still larger scale.

Fig. 5 is a fragmentary perspective view of the upper portion of a pedestal.

Fig. 6 is a partial perspective view of a hanger for a housing.

Briefly in the practice of my invention I mount a conventional drawer housing or runner on a hanger. The housing and hanger together form as a unit, either a right hand housing or left hand housing. The hangers are provided with hook members by means of which they may be removably secured either to the right hand side

20 or the left hand side of a pedestal.

Referring more particularly to the figures, the housing proper, or guide, is indicated at 10. Since the particular guide does not form a part of my invention, I will not describe it further. The guide 15 is secured as by spot welding to a hanger indicated generally at 11. The hanger itself, best seen in Fig. 6, has a lower portion 12 to which the guide 10 is fastened as by spot welding, for example. The upper portion of the hanger is bent at a slight angle to the portion 12 as indicated at 13, so that the portions 12 and 13 are not in the same plane. At the upper edge of the portion 13 are provided two or more hook members 14, which are bent back to occupy a position substantially parallel to the portion 13 and spaced therefrom by the thickness of a pedestal wall.

Also formed along the upper edge of the portion 13 are one or more wings 15 which are bent in the opposite direction to the hook members 14 to substantially a right angle with respect to the portion 13 as clearly shown in Fig. 6.

The desk itself may be of conventional construction having pedestals 16, which are identical and interchangeable. The desk will be provided with a top 17 and may or may not be provided with a skirt 18 across the knee hole portion at the side opposite that on which the user will sit. A center drawer is indicated at 19. The pedestals themselves may be of any desired design or construction, except that if, as is usually the case, the pedestal walls are flanged at the top as indicated at 20, two or more slots 21 will be provided on both walls of the pedestal to accommodate the hook members 14.

55 The desk top may be of any desired design or

construction and will have usually one or more stiffening channels 22.

The guide 10 and its associated hanger 11 is mounted on a pedestal wall, as best seen in Figs. 3 and 4 by hooking the hook members 14 over the top of the pedestal wall through the slots 21 if that pedestal wall has a top flange. By virtue of the slight angle between portions 12 and 13 of the hanger, together with the fact that the hook member 14 is substantially parallel to the portion 13 and fits tightly over the top of the pedestal wall, the hanger will be urged to hug the pedestal wall closely. This action is further enhanced by the wings 15, which are abutted by the stiffening channels 22 when the top is placed on the desk. The desk top bearing on the wings 15 tends to rotate them a small amount in a clockwise direction, as seen in Fig. 4 and this, of course, tends to cause the portions 12 and 13 to be firmly pressed against the pedestal wall with a slight flattening of the angle between the portions 12 and 13. By this construction the housing bears quite tightly against the pedestal wall, so that rattling of the housing is substantially eliminated.

It will be clear to one skilled in the art that numerous modifications may be made without departing from the spirit of my invention and I therefore do not intend to limit myself, except as pointed out in the claims which follow.

Having now fully described my invention what I claim as new and desire to secure by Letters Patent is:

1. A center drawer housing for a pedestal type desk, comprising a drawer guide and a hanger therefor, said hanger comprising a metallic strip having at least two hook members along its upper edge by means of which it may be hung over the top edge of a pedestal wall, and said drawer guide being permanently secured to said hanger, said hanger being of a width to space said drawer guide, below the top edge of said pedestal wall to provide clearance for a drawer mounted therein, the portion of said hanger above said drawer guide being disposed at a slight angle to that portion to which said drawer guide is secured, whereby the central portion longitudinally of said strip tends to lie away from the pedestal wall to which it is removably secured, and means for urging said strip against said pedestal wall.

2. A device according to claim 1, in which said hook members comprise tongues reversely bent with respect to said strip so as to lie parallel to the plane of the upper portion thereof and spaced therefrom by the thickness of the pedestal wall.

3. A device according to claim 2, in which there are two hook members, disposed respectively adjacent each end of said strip.

4. A device according to claim 3, in which said strip is provided with a wing member extending from its upper edge at substantially a right angle in a direction opposite to said hook members, said wing serving as a lever to cause said hanger to hug said pedestal wall when a top is resting on said desk and bearing on said wing.

5. In combination a desk pedestal and a removable housing for a center drawer, said pedestal being symmetrical side for side, and having at least portions of both side wall tops exposed for engagement, said removable housing comprising a drawer guide and a hanger therefor, said hanger comprising a metallic strip having at least two hook members along its upper edge by means of which it may be hung over the top edge of a pedestal wall, and said drawer guide being permanently secured to said hanger, said hanger being of a width to space said drawer guide below the top edge of said pedestal wall to provide clearance for a drawer mounted therein, the portion of said hanger above said drawer guide being disposed at a slight angle to that portion to which said drawer is secured, whereby the central portion longitudinally of said strip tends to lie away from the pedestal wall to which it is removably secured, and means for urging said strip against said pedestal wall.

6. A structure according to claim 5, in which said hook members comprise tongues reversely bent with respect to said strip so as to lie parallel to the plane of the upper portion thereof and spaced therefrom by the thickness of the pedestal wall.

7. A structure according to claim 6, in which there are two hook members, disposed respectively adjacent each end of said strip.

8. A structure according to claim 7, in which said strip is provided with a wing member extending from its upper edge at substantially a right angle in a direction opposite to said hook members, said wing serving as a lever to cause said hanger to hug said pedestal wall when a top is resting on said desk and bearing on said wing.
